RAILWAY SWITCH MECHANISM

Charles C. Thorn, Camden, N. J.

Application December 1, 1933, Serial No. 700,397

23 Claims. (Cl. 246—146)

This invention relates to railway switches, and more particularly to mechanism for locking and unlocking a switch, and to associated mechanism for insuring safety and positiveness of operation under conditions of normal and abnormal service.

One object of the invention is to provide a mechanism through which a switch may be unlocked, reversed and locked again, with the full stroke of the switch throwing device utilized for moving the switch from one extreme position to the other, thereby reducing the power required for the movement of the switch.

Another object of the invention is to provide in such a mechanism means for controlling the operation of electrical contacts, such means being in part responsive directly to the movement of the switch points, and in part responsive to movements involved in locking and unlocking the switch, and such means being designed to give to the switch operator at all times a correct indication of conditions existing at the switch.

Another object of the invention is to provide means for indicating to the switch operator defective conditions, or abnormal deflections of the switch points, such as may result from wheels trailing through a closed switch, or from other circumstances rendering a switch unsafe for the passage of trains, as well as to provide means for safeguarding a defective switch against the passage of a train thereover.

Another object of the invention is to provide point detecting mechanism controlling the operation of electric circuits leading to a remote control station, such mechanism being characterized by capacity for adjustment to conform with switch point openings of various sizes.

Another object of the invention is to provide a device for preventing the switch from being thrown by dragging equipment or other means engaging the pipe line and tending to move the same in one direction or the other, it being important that only the regular operation of the control machine shall cause a movement of the switch.

Another object of the invention is to provide automatic means for unlocking and locking a switch before and after the switch throwing operation, and to this end a reversible motor is utilized, means being provided for starting and stopping the motor as an incident to the regular operation of the control machine. Moreover, additional means are provided for automatically reversing the polarity of the motor to change its direction of rotation so that the motor may cause

a back and forth movement of the mechanism driven by it.

Still other objects and advantages characterizing the present invention will become more fully apparent from the description hereinafter set forth of two embodiments or examples of the practice of the invention, having reference to the accompanying drawings. Of the drawings:

Fig. I represents a general view of a railway switch, showing somewhat diagrammatically the electro-mechanical mechanism of my invention employed at the switch, together with the control lever which is used for operating the switch from a remote station. 10

Fig. II represents an enlarged plan view of the electro-mechanical mechanism employed at the switch. 15

Fig. III represents a longitudinal cross-section of the same, taken as indicated by the lines III—III of Fig. II. 20

Fig. IV represents a transverse cross-section of the same, taken as indicated by the lines IV—IV of Figs. II and V.

Fig. V represents an enlarged fragmentary plan view of certain parts of the mechanism associated with the lock rod and point detector rod, showing such parts in the positions which they normally assume when the switch is locked at the side represented in Fig. I. 25

Fig. VI represents a view similar to Fig. V, 30 with certain elements removed, and showing the parts in the positions assumed when the switch is unlocked and preparatory to throwing the switch.

Fig. VII represents a view similar to Fig. VI, showing the parts in the positions assumed after 35 the switch has been thrown to the other side and re-locked.

Fig. VIII represents a fragmentary plan view of parts of the electro-mechanical mechanism illustrating the action which takes place when 40 the switch is trailed through, or moved by an external force other than the regular switch throwing device.

Fig. IX represents an elevation of a device forming part of the electro-mechanical mechanism and employed for opening and closing certain electrical contacts. 45

Fig. X represents a cross-section, taken as indicated by the lines X—X of Fig. V.

Fig. XI represents a perspective view of a cam 50 plate used for governing the movement of a circuit controller.

Fig. XII represents a perspective view of a blocking crank responsive to movement of the point detector rod. 55

Fig. XIII represents a perspective view of a blocking dog used for safety purposes.

Figs. XIV, XV and XVI represent perspective views of three cam surfaced pieces engaged by the point detector rod.

Fig. XVII represents a perspective view of a thimble associated with a cam piece.

Fig. XVIII represents a perspective view illustrating portions of the lock rod and slide bar, showing the method of locking the switch.

Fig. XIX represents a wiring diagram, showing the electric circuits involved.

Fig. XX represents a plan view similar to Fig. II, but showing a modified form of apparatus.

Fig. XXI represents a view similar to Fig. III of the modified form of apparatus, the view being a cross-section taken as indicated by the lines XXI—XXI of Fig. XX.

Fig. XXII represents a side elevation of toggle mechanism used in the modified form of apparatus, a portion of the view being a cross-section taken as indicated by the lines XXII—XXII in Fig. XX.

Fig. XXIII represents a similar view of the toggle mechanism with the parts moved to opposite positions.

Fig. XXIV represents a perspective view illustrating portions of the lock rod and slide bars used with the modified form of apparatus.

Fig. XXV represents a wiring diagram showing the electrical circuits involved with the modified form of apparatus; and,

Fig. XXVI shows the switch throwing lever used with the modified form of apparatus.

With particular reference to Fig. I of the drawings, there is shown a general plan of a switch with apparatus of my invention applied thereto. The movable point rails of the switch are designated at 1 and the stock rails are designated at 2. Near their free ends the point rails 1 are joined together by a connecting rod 3 to which is attached the customary switch operating rod 4. At the extreme ends of the point rails 1 suitable brackets 5 are provided, and to these brackets a lock rod 6 is attached. To one of the brackets 5 there is also attached a point detector rod 7. Desirably the connection between the point detector rod 7 and the bracket 5 is made through a stud 8 applied at a point near the top of the point rail 1, so that even if the point rail is twisted or otherwise distorted, the point detector rod 7 will follow the movement of the point rail to which it is applied. On the other hand, the lock rod 6 is attached near the base portions of the brackets 5, and, if the switch is trailed through while locked, either the lock rod will break or the point rails 1 or the brackets 5 will become distorted.

60 The mechanical elements of the switch mechanism

In the particular example of my invention selected for illustration, the switch is manually operated through a pipe line 11 leading to a switch throwing lever 12 at a remote station. Portions of the pipe line 11, including right angle cranks 13, are shown conventionally in Fig. I, one end of the pipe line attaching directly to the switch operating rod 4, and the other end attaching to the tail arm 14 of the switch throwing lever 12.

The switch throwing lever 12 is represented to be of an ordinary type commonly used in interlocking machines and includes the usual quadrant 15, rocker 16, latch rod 17 and latch block

18. Connected to the rocker 16 is a latch lock rod 19 which rests upon a stationary member 19 and leads to a cross locking rod 20. Associated with the switch throwing lever 12 there is a relatively small control lever 22 of a type well-known to those skilled in the art, which is operated in conjunction with the large lever 12 and mechanically connected thereto by means of a crank arm 21 and the cross locking rod 20. Opposite positions occupied by the switch throwing lever 12 are represented at N and R in Fig. I, designating arbitrarily "normal" and "reverse" positions respectively. Similarly normal and reverse positions for the small lever 22 are designated at N' and R', with intermediate positions 15 designated at B', C' and D'.

The latch rod 19 is slotted near the end thereof as indicated at x and y, and the cross locking rod 20 is slotted as indicated at z. In order to move the switch throwing lever 12 from normal 20 to reverse position, it is first necessary to release the cross locking rod 20 from the slot x of the latch rod 19. This is accomplished by moving the small lever 22 to the intermediate position C'. Then when the large lever 12 is moved 25 to reverse position R, a second movement of the small lever to reverse position R' causes the cross locking rod 20 to engage the slot y of the latch rod 19 and to lock the large lever 12 in its new position.

In Figs. II and III of the drawings there is shown one form of mechanism of my invention which may be employed adjacent to the switch. The mechanism is housed in a suitable casing, designated at 23, fitted with removable covers 24, 25, as well as a removable section 26 which permits access to all parts thereof. Preferably the casing 23 is secured directly to the switch timbers, though it may be desirable to employ the usual base plate (not shown) beneath the casing. It will be observed that the casing 23 and the mechanism housed therein may be disposed at either side of a switch. If the casing 23 is to be placed at the opposite side of the switch, it is only necessary to change the connections to the switch operating rod 4, the lock rod 6 and the point detector rod 7. Moreover, it will be observed that the switch operating rod 4 passes through the casing 23 and is connected to the pipe line 11 in such manner that the full 50 stroke of the pipe line, as operated by the switch throwing lever 12, is utilized for moving the point rails 1 of the switch from one extreme position to the other extreme position. This is of particular advantage as compared with other types of 55 manually operated switch mechanisms wherein only a fraction of the movement of the pipe line is imparted to the switch operating rod to throw the switch, for the arrangement of my invention reduces the power required to a minimum, 60 and makes a more positive and more convenient operation for the operator throwing the switch lever 12.

The section of the switch operating rod 4 passing through the casing 23 carries thereon a block 65 27 which, when the switch is locked in either of its extreme positions is obstructed by one or the other of two blocking dogs in the form of cranks 28. Each blocking dog 28 has a square shank 29 fitting in a correspondingly shaped socket of a 70 plate 30 which is conveniently designated a "motion" plate. Each dog 28 includes an arm 32 projecting radially from the axis of the shank 29 in the path of the block 27 of the switch operating rod 4. Each dog 28 includes additionally 75

a short arm 33 disposed at an angle to the arm 32 and normally clear of a stationary projection or lug 34 disposed at the inside of the casing 23. The short arms 33 of the dogs 28 are provided with two projecting points 35, 36, one or the other of which under certain conditions when the dog 28 is stressed torsionally beyond its elastic limit are caused to engage one of the stationary lugs 34 at the sides of the casing 23 in a manner such as to prevent movement of the motion plate 30 and cause the mechanism to become inoperative. The detailed construction of one of the dogs 28 is shown clearly in Fig. XIII.

The motion plate 30 is confined between guides 31 for sliding movement within the casing 23 in the direction of its length and is moved by means of an electric motor 38. Movement of the motion plate 30 is accomplished through the medium of a worm gear 39, reduction gears 40, 41, 42 and a pinion 43 which meshes with a rack bar 44 fixed to the motion plate 30. The motion plate 30 also has riveted thereto a slide bar 45, see Fig. III, which serves as a means for engaging and releasing the lock bar 6 and which also serves to 25 actuate a circuit controller 46.

The manner in which the slide bar 45 imparts movement to the circuit controller 46 is clearly shown in Fig. II. The slide bar 45 has secured to its outer end a cam plate 48 having upstanding walls 49 serving as cam surfaces and guiding the movement of a roller 50 on the end of a bell crank lever 51. The bell crank lever 51 has a fixed pivot at 52, and its opposite end is connected to a rack bar 53 which meshes with a pinion 54 on the circuit controller 46. In an obvious manner movement of the slide bar 45 from one extreme position, as represented in Fig. V, to the other, as represented in Fig. VI, causes a corresponding movement of the cam plate 48 which in turn imparts an angular movement to the bell crank lever 51, and through the medium of the rack bar 53 rotates the circuit controller 46 from one position to another. The particular construction of the cam plate 48 is clearly shown in Fig. XI, and it will be observed that the cam surfaces are so configured that two distinct motions are imparted to the bell crank lever 51, causing two distinct motions of the circuit controller 46 in its movement from one extreme position to the other.

The slide bar 45 serves as a means for locking and unlocking the lock rod 6. For this purpose the slide bar 45 is provided with a dog 56 at the end thereof, as shown clearly in Fig. XVIII, which is adapted to engage in one or the other of two slots 57, 58 in the lock rod 6. As shown in Fig. XVIII, the lock rod 6 is preferably made of two pieces, each having a relatively wide and a relatively narrow slot therein, and the narrow slot of one piece being in registry with the wide slot of the other piece. By sliding one such piece with respect to the other, the lock rod 6 may be adjusted in an obvious manner for different sizes of switch point openings. When the switch is in either of its extreme positions, either the slot 57 or the slot 58 of the lock rod 6 is engaged by the dog 56 on the slide bar 45. When the motor 38 is energized, the motion plate 30 moves to the left, as represented in Figs. II and III, causing a corresponding movement of the slide bar 45, which is guided in a channel 59, and causing the locking dog 56 to be withdrawn from the slot 58, of the lock rod 6. The lock rod 6 is guided for movement transversely of the casing 23, by means of guide walls 60, shown most clearly in Figs. III and IV.

Disposed above the roller 50 on the end of the

bell crank lever 51, as shown in Fig. X, there is an upwardly projecting stud 62 which is caused to move transversely of the casing 23 by the action of the cam plate 48 when the slide bar 45 is moved longitudinally of the casing. The stud 62 is engaged within depending projections 63 on a movable blocking bar 64. The blocking bar 64 is most clearly illustrated in Fig. IV. It has capacity for limited transverse movement within the casing 23, and is guided by means of slotted pedestals 5 10 65. At the end of the bar 64 there is carried a blocking piece 66, which serves, as hereinafter explained, to prevent the separation of certain electrical contacts designated at 67a, 67b during the unlocking and locking operations that precede 15 and follow the operation of throwing the switch from one position to the other.

The point detector rod 7, which is attached to the extreme ends of the point rails 1 in the manner previously described, governs the operation 20 of a circuit controller 47, which is disposed adjacent to the previously mentioned circuit controller 46, but which operates independently thereof. On the point detector rod 7, there is carried a roller 69 which is adapted to engage cam pieces 25 70, 71, 72, associated with a crank 73 fixed on a shaft 74. The cam pieces 70, 71, 72 are shown in detail in Figs. XIV, XV and XVI, and are of such nature that the crank 73 will be moved with the same stroke for all switch point openings. 30

As shown in Fig. II, the shaft 74 has its ends supported for rotation in bearing pieces 75 on the sides of the casing 23. To the shaft 74 are pinned the central cam piece 71, the crank 73, and an arm 76 disposed at the opposite ends of 35 the shaft 74 from the crank 73. A bar 77 rigidly connects the crank 73 with the central cam 71 and the arm 76. In the example illustrated, the bar 77 is of rectangular cross-section and engages within a correspondingly-shaped slot on 40 the central cam piece as indicated at 79 in Fig. XV. Similarly shaped slots are formed in the crank 73, as indicated at 80, in the end cam pieces, as indicated at 81 in Figs. XIV and XVI, and in the arm 76. The end cam pieces 70, 72 are not, 45 however, bolted to the bar 77, but have a sliding connection therewith permitting their adjustment in the manner hereinafter explained.

The cam pieces 70, 71, 72 are so constructed as to form a cam path for the roller 69 on the point 50 detector rod 7 as diagrammatically indicated in Fig. V at 82, the path being characterized by abruptly inclined cam surfaces near each end thereof, which serve to impart two distinct movements to the crank arm 73 incident to the full stroke of 55 the point detector rod 7, in the direction represented by the arrow in Fig. V. The end cam pieces 70, 72 which are illustrated in detail in Figs. XIV and XVI, respectively, are adjustably secured to the shaft 74 by means of internally 60 threaded thimbles 83 and jamb nuts 84. One such thimble 83 is shown in detail in Fig. XVII. It will be noted that the shaft 74 is threaded at each side of the central cam piece 71. To set the movable cam pieces 70, 72 in new positions on 65 the shaft 74 involves merely releasing the jamb nuts 84, turning the thimbles 83, and re-locking the jamb nuts 84. The jaw-shaped depending projections of the cam pieces 70, 71, 72 are so formed as to provide a continuous cam path for 70 the roller 69 extending from one side of the casing 23 to the other. As shown in Fig. IX, the jaw-shaped projections 85 of the central cam piece 71 are disposed above the jaw-shaped projections 86 of the cam pieces 70, 72 so as to over- 75

lap the same. In the illustrated example, the cam pieces 70, 71, 72 are set in the positions which they occupy for the maximum size switch point opening to which the apparatus is adapted for use. When it is desired to reset the apparatus for a smaller switch point opening, the end cam pieces 70, 72 are moved inward toward the central cam piece 71 and fixed in positions corresponding to the size of the switch point opening.

10 The crank 73 has a bifurcated end 81 with a pin 88 which engages a rack bar 89. Rotation of the crank 73 in opposite directions imparts a reciprocatory movement to the rack bar 89, and through the medium of a pinion 90 meshing with 15 the teeth of the rack 89, imparts rotary movement to the circuit controller 47. In Fig. IX, the two extreme positions of the crank 73 are indicated, one in full lines, and the other in dot-and-dash lines. It will be noted that the circuit controller 20 47 moves from one position to another in direct relation to the movement of the point rails 1 of the switch.

As most clearly shown in Fig. V, the rack bar 25 89 has thereon a bracket 91 which extends downward and inward and terminates in a bifurcated end engaging a pin 92 on one end of a blocking crank 93 which is pivoted at 94. The construction of the blocking crank 93 is shown in detail in Fig. XII, and it will be particularly observed 30 that this element has two upstanding lugs 95 in spaced relation along an arcuate surface 96. The lugs 95 prevent movement of a spring urged plunger 97, while the switch points are at either limit of their travel. The plunger 97, as most 35 clearly illustrated in Fig. IX, has an expanded end 98 disposed between blocks 99 connected across the electrical contact members 67a, 67b. The plunger 97 is at all times under the influence of a spring 100, disposed within a cylinder 101, 40 which spring engages the opposite end of the plunger 97 and tends to withdraw the expanded end 98 between the blocks 99, and thus tends to separate the electrical contact members 67a, 67b.

During the regular operation of the switch 45 mechanism, there is no occasion for movement of the plunger 97 which is employed merely as a safety feature operating in certain emergencies. When the switch is in either of its two extreme 50 positions, the normal position being represented in Fig. V and the reverse position in Fig. VII, movement of the plunger 97 is prevented by virtue of the engagement of one of the lugs 95 of the blocking crank 93 against the collar 102 of the plunger. Moreover, as most clearly shown in 55 Fig. IV, whenever the switch is unlocked preparatory to movement from one position to the other, movement of the slide bar 45 causes a transverse movement of the blocking bar 64 above the lock rod 6 and causes the blocking piece 66 to assume a 60 position in front of the collar 102 of the plunger 97. Hence, while the blocking crank 93 is moving from one position to another, in the normal operation of the switch, as soon as a lug 95 of the blocking crank 93 is withdrawn from engagement 65 with the collar 102 of the plunger 97, the blocking piece 66 will come into play and obstruct movement of the plunger 97. By the construction described above, operation of the plunger 97 is effectively prevented during all normal operations 70 of the switch. If, however, the point rails 1 of the switch are caused to be distorted while the switch mechanism is locked, as may occur when the switch is trailed through by the wheels of a vehicle, or by equipment dragged between 75 closed point and stock rails, there is no obstruc-

tion to movement of the plunger 97, and the electrical contact members 67a, 67b will become separated, opening certain electrical circuits herein-after described, and giving an indication to the switch operator of the defective condition of the 5 switch, as well as causing a restrictive indication of the signals associated with the switch.

The electrical elements of the switch mechanism

In Fig. XIX of the drawings, the electrical circuits of the apparatus employed at the switch, as well as the apparatus employed at the control station, are diagrammatically represented. At the left hand side of the figure, the electrical contacts 67a, 67b, which are opened and closed by 10 the movement of the plunger 97, are shown together with the circuits leading through the motor 38, and the two circuit controllers 46, 47. The contacts of the circuit controller 46 are designated by the numerals 104, 105, 106, 107. 15 The contacts of the circuit controller 47 are designated by the numerals 108, 109, 110, 111. At the right hand side of Fig. XIX, the small lever 22, employed at the control station, is shown together with parts of the cross locking mechanism 20 by which the small lever 22 and switch throwing lever 12 are mechanically connected. To the shaft 112, associated with the small lever 22, are attached arcuate brackets 113, 114 of a well-known type which cooperate with latch members 25 115, 116, operated respectively by a reverse indication magnet 117, and a normal indication magnet 118. The electrical circuits also involve a polarized relay WR having contact members 119, 120, 121, 122, and a polarized relay SS having contact members designated by the numerals 30 123 to 130, inclusive.

The contacts 104 to 111 of the circuit controllers 46, 47 are so formed, as diagrammatically illustrated, that the circuits associated therewith 35 are opened and closed in accordance with the following plan:

Contact 104 opens only when the lock rod 6 is completely locked.

Contact 105 opens only when the lock rod 6 is 45 completely unlocked.

Contacts 106, 107 are closed only when the switch is locked.

Contacts 108, 109 are closed only when the 50 switch is in normal position.

Contacts 110, 111 are closed only when the switch is in reversed position.

Associated with the small lever 22 there are a series of electrical contacts made and broken by movement of the lever 22 in accordance with 55 the following plan:

Contact B'' is made only when the small lever 22 is in the position designated at B'.

Contact D'' is made only when the small lever 22 is in the position designated at D'. 60

Contact C'' is made only when the small lever 22 is in the position designated at C'.

Contact C''' is made only when the small lever 22 is in the position designated at C'. 65

Contact B''' is made only when the small lever 22 is in the position designated at B'.

Contact D''' is made only when the small lever 22 is in the position designated at D'. 70

Contact NB is made only when the small lever 22 is in the position designated at N', in the position designated at B', and between said positions.

Contact RD is made only when the small lever 22 is in the position designated at R', in the 75

position designated at D', and between said positions.

The various conductors, battery terminals, and other devices included within the electric circuits, and not already referred to, are given reference numerals in the description of the operation of the switch mechanism which follows hereinafter. It will be observed that all of the electric circuits which lead to the switch mechanism in the casing 23 are conveniently connected to a terminal board 134, shown in Figs. II and XIX.

Normal operation of the switch mechanism

The normal operation of the mechanical and electrical mechanism is as follows. Let it be assumed that all the parts of the apparatus, including devices employed at the control station, as well as those housed within the casing 23 at the switch, are in the positions which have been arbitrarily designated as "normal" positions. The mechanical elements assume the positions shown in Figs. II and V, and the electrical elements assume the positions shown in Fig. XIX. The polarized relay SS is energized in such manner as to maintain its contacts 123, 125, 127, 129 in raised position and its contacts 124, 126, 128, 130 shifted to the left, the circuit being completed as follows. Current flows from positive battery 165 through terminal 166 of the terminal board 134, conductor 167, point detector contact 67b, conductor 168, contact 108 of the circuit controller 47, conductor 176, contact 107 of the circuit controller 46, conductor 175, terminal 174, conductor 173, relay SS, conductor 172, terminal 171, conductor 170, contact 106 of the circuit controller 46, conductor 169, contact 109 of the circuit controller 47, conductor 177, point detector contact 67a, conductor 178, terminal 157 to negative battery 158.

When it is desired to throw the switch to the reverse position, the first act performed by the operator is to move the small lever 22 at the control station from position N' to position C'. As the small lever 22 passes through the position B', relay WR is energized. Current flows from positive battery as designated at 135, through conductor 136, contact B'', conductor 137, conductor 138, the relay WR, conductor 139, conductor 140, contact B'' to negative battery 141.

When the relay WR is thus energized, its contacts 119, 121 are lifted, and its contacts 120, 122 are moved to the right. The motor 38 remains at rest, because the circuits associated therewith include contact 104 of the circuit controller 46 which contact is opened whenever the lock rod is completely locked.

When the small lever 22 reaches the position designated at C', the polarized relay WR is energized by current flowing in the opposite direction from that described above. Under these circumstances, current flows from positive battery 135, through conductor 136, contact C'', conductor 139, relay WR, conductor 138, contact C'', conductor 142 to negative battery 141. When the polarized relay WR is thus energized, its contacts 119, 121 are lifted, and its contacts 120, 122 are moved to the left. With the relay WR thus energized, current flows from positive battery 143, through contact 120, conductor 144, contact 119 lifted, conductor 145, terminals 146, 147 of the terminal board 134 to the armature of the motor 38, thence through terminals 149, 150 of the terminal board 134, through conductor 151, contact 121 lifted, conductor 161, contact 122, conductor 153, terminal 154, conductor 155, con-

tact 105 of the circuit controller 46, conductor 156, the field windings F of the motor 38, and terminal 151 to negative battery 158.

When the motor 38 is started in operation, the motion plate 30, together with the slide bar 45, is moved to the left, as the apparatus is viewed in Fig. II. Movement of the slide bar 45 withdraws the dog 56 from the slot 58 of the lock rod 6, thus unlocking the switch. Movement of the motion plate 30 to the left also withdraws the blocking dogs 28 from positions obstructing the switch operating rod 4. Movement of the motion plate 30 also causes a transverse movement of the blocking bar 64 disposed above the lock rod 6, this being accomplished through the medium of the cam plate 48 and the stud 62. Such movement of the blocking bar 64 brings the blocking piece 66 to a position in advance of the collar 102 on the plunger 91, and prevents opening of the electrical contact members 67a, 67b.

As the motion plate 30 commences to move toward the left, the cam plate 48 imparts one movement to the crank arm 51, and through the medium of the rack bar 53 imparts a movement to the circuit controller 46, breaking contact 104 thereof. Just before the motion plate 30 reaches its extreme left-hand position, as represented in Fig. VI, the cam plate 48 imparts a second movement to the crank arm 51 which, through the medium of the rack bar 53, completes the reversal of the circuit controller 46. With the circuit controller 46 thus reversed, its contact 105 opens, breaking the hereinbefore described circuit leading to the motor 38 and causing the motor to stop.

At this point, assuming that all the parts have operated in the regular accustomed manner, the switch is in readiness to be thrown to the reversed position. It will be noted that the movement of the small lever 22 to the position C' has lowered the cross locking rod 20 so that it disengages the slot x of the latch lock rod 19, thus preparing the switch throwing lever 12 for operation. The operator thereupon pulls the latch rod 17 of the switch throwing lever 12 and swings the switch throwing lever 12 from the normal position N to the reversed position R. With the resulting movement of the pipe line 11 and the switch operating rod 4, the point rails 1 of the switch are shifted from one extreme position to the other. While the point rails 1 are thus shifted, the point detector rod 7 which follows their movement is urged transversely through the casing 23, and its roller 69 engages the cam pieces 70, 71, 72, imparting a swinging movement to the crank 73, and a reciprocatory movement to the rack bar 89, which turns the circuit controller 47 from its normal position to the opposite or reverse position. At the same time, the blocking crank 93 reverses its position, and its lugs 95, together with the blocking piece 66, prevent actuation of the plunger 91, and thus prevent opening of the electrical contacts 67a, 67b.

When the circuit controller 47 is reversed, as described above, its contacts 108, 109, are opened, and its contacts 110, 111 are closed. In order to lock the switch in its reverse position, the operator moves the small lever 22 from the position C' toward the position R'. As the lever 22 passes over the position D', the motor 38 is started in operation in a direction such as to return the motion plate 30 and the slide bar 45 to their original positions. Under these circumstances, current flows from positive battery 135 through conductor 136, contact D'', conductor 137, con-

ductor 138, relay WR, conductor 139, conductor 140, contact D'', conductor 142 to negative battery 141. The polarity of the relay WR thus energized is such as to move its contacts 120, 122 to the right. Accordingly, current flows in the motor circuit from positive battery 143 through conductor 160, contact 122, conductor 161, contact 121, conductor 151, terminals 150, 149 to the armature of the motor 38, thence through terminals 147, 146, conductor 145, contact 119 lifted, conductor 144, contact 120 shifted to the right, conductor 162, terminal 163, conductor 164, contact 104 of circuit controller 46, conductor 156, the field winding F of the motor 38, terminal 157 to negative battery 158. With operation of the motor 38 in the manner described, the motion plate 30 and slide bar 45 are moved to the right, back to the position shown in Fig. II; and this movement is accompanied by a movement of the crank 51 and rack bar 53 such as to return the circuit controller 46 to its original position. When the circuit controller 46 is returned to its original position, its contact 104 opens, breaking the circuit to the motor 38 and causing the motor to stop.

Whenever the relay WR is de-energized, it will be observed that the armature of the motor 38 is short circuited over conductor 145, contact 119 dropped, conductor 152, contact 121 dropped and conductor 151.

With the switch thus thrown to reverse position and relocked in that position, relay SS is energized in the following manner. Current flows from positive battery 165 through terminal 166, conductor 167, point detector contact 67b, conductor 168, contact 110 of circuit controller 47, conductor 169, contact 106 of circuit controller 46, conductor 170, terminal 171, conductor 172, relay SS, conductor 173, terminal 174, conductor 175, contact 107 of circuit controller 46, conductor 176, contact 111 of circuit controller 47, conductor 178, and terminal 157 to negative battery 158. With the relay SS energized with current flowing as described, its contacts 123, 125, 127, 129 are lifted and its contacts 124, 126, 128, 130 are shifted to the right. Current is then permitted to flow from positive battery 135 through contact RD, conductor 179, contact 123 lifted, contact 124, shifted to the right, conductor 180, reverse indication magnet 117, conductor 181, to negative battery 182. The reverse indication magnet being energized, its latch member 115 is lifted to clear the stop 183 on the arcuate bracket 113, thus making it possible to move the small lever 22 to the position R'. The energization of the relay SS also involves movement of contacts 127 to 130, which set up signal circuits, not shown, giving the proper indication along the track.

At this point in the operation, the small lever 22 may complete its movement to position R'. In so doing the crank 21 and cross locking rod 20 are moved downward into engagement with slot 25 of the latch lock rod 19, thus mechanically locking the large switch throwing lever 12.

In returning the switch from reverse position to normal position, the operations are substantially the same as those described above. However, in moving the small lever 22 from the position C' toward the position N', after the switch has been returned to normal position and relocked, the normal indication magnet 118 is energized when the small lever 22 is in the position 75 B', making possible its movement to the position

N'. Under these circumstances, current flows from positive battery 135 through conductor 136, contact NB, conductor 184, contact 125, contact 126, conductor 185, normal indication magnet 118, conductor 186, to negative battery 182. With the normal indication magnet 118 energized, its latch member 116 is raised to a position clear of the stop 187, making possible the complete movement of the small lever 22 to the position N'. 5

Abnormal operation of the switch mechanism 10

If, while the switch is locked in either extreme position, a train should trail through the switch, or equipment should be dragged through the switch, having the same effect, the point detector 15 rod 7 will be caused to move with corresponding movement of the crank 73, the rack bar 89, and the blocking crank 93, but there will be no movement of the bar 64; and consequently the plunger 97 will be free to move under the influence of the 20 spring 100, and the point detector contacts 67a, 67b, as illustrated in Fig. VIII, will be separated until the plunger 97 is restored by hand to its normal position. When the point detector contacts 67a, 67b are separated, the circuit is broken 25 to the relay SS with the result that contacts 127 to 130 involved in the signal circuits are opened, thus giving a restrictive indication along the track, and with the further result that contacts 123 to 126 of the relay SS are opened, preventing 30 operation of either the reverse indication magnet 117 or the normal indication magnet 118, and thus making it impossible for the operator to go through the regular movements involved in throwing the switch. Moreover, where a warning device, such as a light or bell, is provided at the control station, such devices being in common use and therefore not shown in the drawings, the operator is immediately notified of the 35 defective condition. 40

When a switch is trailed through, or when equipment is dragged through the switch, the mechanical elements disposed adjacent to the switch are placed out of commission. The blocking dogs 28 are of such physical proportions that 45 movement of the switch operating rod 4, which is a relatively strong rod, will distort the particular dog 28 which is engaged by the blocking piece 21, causing the long arm 32 and short arm 33 to give in torsion with respect to the square shank 50 29 in the manner represented in Fig. VIII. Depending upon the angular movement thus imparted to the arms 32, 33 of the dog 28, either the point 35 or the point 36 of the distorted crank 55 will move into the path of the stationary lug 34 55 on the casing 23, and thus movement of the motion plate 30 will be effectively prevented so that the mechanism cannot be unlocked. Moreover, attention is drawn to the operator at the control station that the mechanism is out of order, for he 60 cannot throw the switch and must proceed to make repairs. In such manner the blocking dogs 28 function in effect as mechanical point detectors.

The dogs 28 are of such physical proportions 65 that if the switch is locked and the pipe line 11 should become entangled with passing equipment, or if some force, other than the force regularly applied by the switch throwing lever 12, should be applied to the pipe 70 line 11, tending to move the switch, the pipe line 11 or some of the parts connected thereto will part before the dog 28 will give in torsion about its shank 29, thus protecting the switch points from being moved from their proper position. In 75

other words, each crank dog 28 offers such resistance to torsional stress that it will give way before parting of the operating rod 4, but not before parting of the pipe line 11, under external forces applied at the switch and pipe line respectively.

The modified form of switch mechanism

In Figs. XX to XXVI, inclusive, there is shown a modification of the apparatus of my invention, involving certain changes in the mechanical and electrical elements employed. The mechanical elements embodied in the casing 23b, which is adapted to be disposed alongside the switch, are similar to those already described and hence are designated by the same reference numerals, with the following exceptions. In the modified form of apparatus, the motion plate 30b has a longer travel than the previously described motion plate 30, and in moving the switch from normal to reverse position the motion plate 30b is given two motions in the same direction. When the switch is later restored to normal position, the motion plate 30b is moved twice in the opposite direction. The motion plate 30b carries thereon two blocking dogs 28b which are disposed on opposite sides of the switch operating rod 4. Attached to the motion plate 30b are two slide bars 45b, 45c, most clearly illustrated in Fig. XXIV, carrying at their ends dogs 56b, 56c. The lock rod 6b has one slot 58b at its under side, and has a similar slot 57b at its upper side. While the lock rod 6b is shown as a one-piece rod, it may be rendered adjustable in the same manner as the previously described lock rod 6. In its normal position the motion plate 30b is at the left, as indicated by the full lines in Fig. XX. In this position the slide bar dog 56c engages in the slot 58b of the lock rod 6b. With the first movement of the motion plate 30b to the right, the slide bar dog 56c is released from the slot 58b, as illustrated in Fig. XXIV, and the parts are unlocked and in readiness for switch throwing. With the second movement of the motion plate 30b to the right, which follows after the switch is reversed, the slide bar dog 56b enters into the slot 57b of the lock rod 6b.

In the modified form of apparatus, the slide bar 45b carries at the end thereof a cam plate 48b having upstanding walls 49b which define a cam path of more gradual inclination than the cam path of the plate 48 employed with the first described form of apparatus. Near the circuit controller 46, there is a reversing switch 188 having spring contact members 188a, 188b, 188c, which are used for changing the polarity of part of the circuits to the motor 38 after the motion plate 30b has completed its movement in one direction, in order that it may be prepared for movement in the reverse direction for the next switch operation. As shown in Figs. XXII and XXIII, the electrical contact members 188a, 188b, 188c are normally held in lowered positions, as indicated in Fig. XXII, by means of a block 190 carried on a bell crank lever 191 pivoted at 192. Movement of the motion plate 30b from left to right causes the spring contact pieces 188a, 188b, 188c to be urged upward to the position shown in Fig. XXIII through the medium of the bell crank lever 191 and a toggle mechanism 193. The toggle switch 193 includes a plate 194 fastened to the casing 23b and having thereon stops 195. On the plate 194 there is pivoted a lever 196 having a downwardly directed finger 197 and an additional lever 198 having a like finger 199. The levers 196, 198

are connected by a rod 200 which carries a pin 201 in engagement with one end of the bell crank lever 191. Toggle elements 202 and a spring 203 are associated with the lever 196. The spring 203 surrounds a rod 204 pivoted at 205. It will be apparent that the toggle mechanism is of such construction that the levers 196, 198 are forced by the spring 203 to assume either the position shown in Fig. XXII or that shown in Fig. XXIII.

The motion plate 30b carries thereon a roller 206 which is adapted to engage alternately the fingers 197, 199 of the toggle mechanism 193. As the motion plate 30b moves from left, as shown in Fig. XXII, to right, as shown in Fig. XXIII, the roller 206 strikes the finger 199, moving the bar 200 to the left and imparts a clockwise motion to the bell crank lever 191, causing the spring contact pieces 188a, 188b, 188c to move upward. Similarly when the motion plate moves from right to left, the roller 206 strikes the finger 197, moving the rod 200 to the left and imparting a counter-clockwise movement to the bell crank lever 191, causing the spring contact piece 188a, 188b, 188c to move downward. The stops 195 limit the positions of the levers 196, 198.

The remaining mechanical elements of the modified form of apparatus are precisely similar to the elements involved in the first described form of apparatus.

In Fig. XXV of the drawings, the electrical circuits and the modified form of apparatus employed at the switch, as well as the apparatus employed at the control station, are diagrammatically represented. At the bottom of the figure there are shown the electrical contacts 67a, 67b, opened and closed by movement of the plunger 97, the circuit controller 46 with its contacts 104b to 107b, the circuit controller 47 with its contacts 108b to 111b, inclusive, the motor 38 with its field winding F, the terminal board 134, a positive battery designated at 165, and a negative battery designated at 158. All of these parts are precisely the same as in the first described form of apparatus and are given the same reference numerals, except that the contacts 104b to 111b of the circuit controllers 46, 47 are so formed, as diagrammatically illustrated, that the circuits associated therewith are opened and closed in accordance with a different plan as follows:

Contact 104b opens when the switch is unlocked in the normal position.

Contact 105b opens when the switch is unlocked in the reverse position.

Contact 106b opens only when the switch is completely locked in normal or reverse position.

Contact 107b is closed only when the switch is completely locked in normal or reverse position.

Contacts 108b, 109b are closed only when the switch is in normal position.

Contacts 110b, 111b are closed only when the switch is in reverse position.

There is also shown at the bottom of the figure the electrical reversing switch 188 with its contact members 188a, 188b, 188c. The relay WR' differs from the previously described relay WR in 65 that it is not polarized. Its contacts are designated at 208, 209.

In the upper part of the figure there are shown the small lever 22, the reverse indication magnet 117 and its associated parts, the normal indication magnet 118 and its associated parts, the cross locking mechanism, the relay SS with its contacts 123 to 130, a positive battery 135 and a negative battery 182. All of these parts are similar to corresponding parts used with the first described 75

form of apparatus, and hence are designated by the same reference numerals and characters. The several positions to which the small lever 22 is adapted to be moved are designated at N', B', C', D', R'. The electrical contacts opened and closed by movement of the small lever 22 are made and broken by movement of the lever in accordance with the following plan.

Contact C'' is made only when the small lever 22 is in the position designated at C'.

Contact D'' is made only when the small lever 22 is in the position designated at D'.

Contact B'' is made only when the small lever 22 is in the position designated at B'.

Contact BCD is made only when the small lever 22 is in the positions designated at B', C' and D', and intermediate points.

Contact BCD' is made only when the small lever 22 is in the positions designated at B', C' and D', and intermediate points.

Contact CB is made only when the small lever 22 is in the positions designated at C' and B', and intermediate points.

Contact CD is made only when the small lever 22 is in the positions designated at C' and D', and intermediate points.

Contact NB is made only when the small lever 22 is in the positions designated at N' and B', and intermediate points.

Contact RD is made only when the small lever 22 is in the positions designated at D' and R', and intermediate points.

At the top of the figure there are also shown two stick relays designated at SN and SR. The relay SN has two contacts 210, 211 and the relay SR has two contacts 212, 213. In the circuits to the stick relays SN, SR, there are three electrical contacts 214a, 214b, 214c, which form part of a circuit controller designated by dot-and-dash lines in Fig. XXV at 214. The circuit controller 214 is actuated by the tail arm 215 of the switch throwing lever 12b, as shown in Fig. XXVI. The switch throwing lever 12b, used with the modified form of apparatus, has connected to its tail arm 45 215 a link 216 which in turn engages a crank 217 associated with the circuit controller 214. When the switch throwing lever 12b is in its normal position, contact members 214a, 214b, 214c all occupy the positions represented in Fig. XXV. 50 When, however, the switch throwing lever 12b is reversed, the contact members 214a, 214b, 214c, are caused to move downward. The contact member 214a, for example, is normally in engagement with the contact point 218. When the 55 switch lever 12b is reversed, contact is broken at the point 218 and made at the point 219. It is important to note, however, that the movable contact member 214a is of such construction that contact is made at the point 219 before contact 60 is broken at the point 218. The contact members 214b, 214c, operate simultaneously with the contact member 214a and in the same manner. The various conductors, battery terminals, and other devices included within the electric circuits and not before referred to are given reference numerals in the description of the operation of the modified form of apparatus which follows hereinafter.

Normal operation of the modified form of apparatus

The normal operation of the electrical and mechanical mechanism of the modified form of apparatus is as follows: Let it be assumed that 75 all the parts of the apparatus, including devices

employed at the control station, as well as those housed within the casing 23b at the switch, are in the positions which have been arbitrarily designated as "normal" positions. The mechanical elements assume the positions shown in Figs. XX, 5 XXI and XXII, and the electrical elements assume the position shown in Fig. XXV. When it is desired to throw the switch to the reverse position, the first act performed by the operator is to move the small lever 22 at the control station 10 from position N' to position C'. As the small lever 22 passes the position B', the only circuit that is completed is a circuit through the normal indication magnet 118 as follows. Current flows from positive battery 135, through conductor 220, contact NB, conductor 221, contact 125 normally lifted and contact 126 normally shifted to the left, through conductor 222, normal indication magnet 118, conductor 223, to negative battery 182. When the normal indication magnet 118 is 20 energized, the latch member 116 is raised, but such movement of the latch member 116 is of no particular significance at this point in the operation.

When the small lever 22 reaches the position 25 C', the relay WR' is energized as follows. Current flows from positive battery 135 through conductor 220, contact CD, conductor 210, contact 214a raised of the circuit controller 214, conductor 211, relay SR to negative battery 272, energizing the relay SR and raising its contacts 212, 213. The raising of contact 213 of the relay SR completes a circuit through the relay WR' with current flowing from positive battery 135, through conductor 220, contact BCD', conductor 273, contact 213 lifted of relay SR, conductor 214, relay WR', conductor 215, contact BCD, to negative battery 276.

When the relay WR' is thus energized, its contacts 208, 209 are raised. Instantaneously, 40 current flows from positive battery 225, through contact C'', conductor 226, terminal 227 of the terminal board 134, conductor 228, to contact 104b of the circuit controller 46. This contact being closed, current continues to flow through conductor 279 to contact 188a, of reversing switch 188, conductor 230, conductor 231, terminal 232, the field winding F of the motor 38, to terminal 233, and thence through conductor 234, contact 188b of the reversing switch 188, conductor 235, to terminal 236, and thence through conductor 237, contact 209 of relay WR', conductor 242, terminal 241, to the armature of the motor 38, thence to terminal 240, conductor 239, contact 208 of the relay WR', conductor 244, terminal 245, conductor 246, contact 188c of the reversing switch 188, conductor 247, terminal 248 to negative battery 158. The motor 38 then starts in a direction such that the motion plate 30b is moved to the right a distance sufficient to move the blocking dog 28b out of the path of the switch operating rod 4, and sufficient to move the blocking dog 56c of the slide bar 45c out of engagement with the slot 58b of the lock rod 6b. The slide bars 45b, 45c thus assume the 65 positions shown in Fig. XXIV, and when the parts reach this position through the action of the cam plate 48b and the crank arm 51, the circuit controller 46 is operated and its contact 104b opens. Opening of the contact 104b 70 of the circuit controller 46 breaks the previously described circuit to the motor 38 and causes the motor to stop, with the motion plate 30b in its intermediate position.

Movement of the circuit controller 46 inci- 75

dent to the unlocking of the switch also opens contact 107b thereof. Up until this point the relay SS has been energized over a circuit including contact 107b with current flowing from positive battery 165 through terminal 249, conductor 250, point detector contact 67b, conductor 251, contact 107b of the circuit controller 46, conductor 252, contact 108b, conductor 253, terminal 254, conductor 255, relay SS, conductor 256, terminal 257, conductor 258, contact 109b, conductor 259, point detector contact 67a, conductor 260, terminal 248, to negative battery 158. With the relay SS thus de-energized upon the unlocking of the switch mechanism, its contacts 123 to 130 drop. All circuits to the reverse and normal indication magnets 117, 118 are broken.

With the mechanism thus unlocked, the operator moves the switch throwing lever 12b from normal to reverse position. Incident to this movement of the switch through the action of the point detector rod 7, the circuit controller 47 is actuated and reversed in its position. Also, through the tail arm 215 of the switch throwing lever 12b, the link 216, and the crank arm 217, the circuit controller 214 is actuated, this action resulting in the movement of contact members 214a, 214b, 214c to depressed position as viewed in Fig. XXV.

It will be noted that as the switch throwing lever 12b is moved to reverse position, the relay SR remains energized, for the contact member 214a engages the contact point 219 before it disengages the contact point 218. With the switch reversed, the relay SR is energized over a circuit from positive battery 135 through conductor 220, contact CD, conductor 270, contact member 214a, contact point 219, conductor 271, contact 212, through the relay SR to negative battery 272. Accordingly, the relay WR' remains energized over the circuit previously described, and its contacts 208, 209 remain lifted.

To lock the switch mechanism, the operator then proceeds to move the small lever 22 from position C' to R'. As the small lever 22 reaches the intermediate position D', current flows from positive battery 225, through conductor 261, contact 214c, conductor 262, contact D', conductor 263, terminal 264, conductor 265, contact 106b, of circuit controller 46 (which it will be noted is closed when the switch is unlocked), conductor 266, conductor 231, terminal 232, the field winding F of the motor 38, terminal 233, conductor 234, contact 188b, conductor 235, terminal 236, conductor 237, contact 209 of the relay WR', conductor 242, terminal 241, to the armature of the motor 38, terminal 240, conductor 239, contact 208 of the relay WR', conductor 244, terminal 245, conductor 246, contact 188c of the electrical reversing switch 188, conductor 247, terminal 248 to negative battery 158. Accordingly, the motor 38 is again started in operation in the same direction as it operated before, and the motion plate 30b is given an additional movement to the right, causing the dog 56b of the slide bar 45b to enter into the slot 57b of the lock rod 6b, thus relocking the mechanism. Movement of the motion plate 30b to the right also imparts a second movement to the circuit controller 46 opening contact 106b thereof, and breaking the previously described circuit to the motor 38, thus causing the motor to stop. Upon the assumption that all the parts have operated in the regular accustomed manner, the last described movement results in a favorable indication to the operator at the control station

through the energization of the relay SS. The contact 107b of the circuit controller 46, which closes when the switch mechanism is completely locked in the reverse position, completes a circuit through the relay SS as follows. Current flows from positive battery 165, through terminal 249, conductor 250, contact member 67b, conductor 251, contact 107b, conductor 252, contact 110b, conductor 258, terminal 257, conductor 256, relay SS, conductor 255, terminal 254, conductor 253, contact 111b, conductor 259, point detector contact 67a, conductor 260, terminal 248 to negative battery 158. With the relay SS thus energized with a different polarity, its contacts 123, 125, 127, 129 are lifted and its contacts 124, 126, 128, 130 are moved to the right, setting up the proper indication in the signal circuits. Under these circumstances, current flows from positive battery 135 through contact RD, conductor 267, contacts 123, 124 of the relay SS, conductor 268 to the reverse indication magnet 117, and then through conductor 269 to negative battery 182. Accordingly, the latch member 115 is raised, clearing the stop 183 of the arcuate bracket 113, making it possible to complete the movement of the lever 22 to position R'. With a favorable indication thus received at the control station, the operator thereupon moves the lever 22 to the position R', and through the action of the cross locking rod 20, the switch throwing lever 12b is relocked in its reverse position.

It will also be noted that when the switch is thus reversed, and locked in reverse position, the motor 38 is prepared for operation in the reverse direction by movement of the members 188a, 188b, 188c of the reversing switch 188, through the action of the toggle mechanism 193. This movement occurs when the motion plate 30b reaches its extreme position to the right as represented in Fig. XXIII. Accordingly, when the operations described above are repeated, to return the switch from reverse position to normal position, the motor 38 is energized with current flowing in its armature in the reverse direction, the path of the current under these conditions being from positive battery 225, through conductor C'', conductor 226, terminal 227, conductor 228, contact 105b, conductor 278, contact 188a lifted, conductor 230, conductor 231, terminal 232, field windings F of motor 38, terminal 233, conductor 234, contact 188b lifted, conductor 246, terminal 245, conductor 244, contact 208, conductor 239, terminal 240, the armature of the motor 38, terminal 241, conductor 242, contact 209 of the relay WR', conductor 237, terminal 236, conductor 235, contact 188c lifted, conductor 247, terminal 248 to negative battery 158.

Abnormal operation of the electric circuits of the modified form of apparatus

It not infrequently happens that the operator at the control station may move the small lever 22 of an interlocking machine used with my invention from the position N' to the position C', and then realizing that he has made a mistake, and that he has operated the small lever associated with the wrong switch, he may desire to return the small lever 22 to the position N' without having to go through the movements of throwing the corresponding large lever 12b to reverse position and then back again to normal position. In order to make possible the return of the small lever 22 from the position C' to the position N', without movement of the large lever

12b, the stick relays SN, SR and back contacts of the relay WR' are provided. When the operator has mistakenly moved the lever 22 from the position N' to the position C', unlocking the switch mechanism, he may proceed to return the small lever 22 to the position N', and such movement involves the following operation of the circuits involved. When the small lever 22 rests on the position C', a circuit is completed from positive battery 135 through conductor 220, contact CD, conductor 270, contact 218, conductor 271, through relay SR, to negative battery 272, thus energizing the relay SR and raising its contacts 212, 213.

With the contact 213 raised, the circuit is completed through the relay WR', and that relay is energized. As the small lever 22 is moved back to the position B', the circuit is broken through the relay SR, its contact 213 is dropped, and this in turn opens the circuit to the relay WR', causing its contacts 208, 209 to drop. Dropping of the contacts 208, 209 of the relay WR' reverses the direction in which current passes through the armature of the motor 38. Assuming that the operator intends to throw the switch from normal to reverse position, but when the small lever 22 has reached the point C', he decides not to throw the switch but to return the small lever to the position N', the dropping of the contacts 208, 209 of the relay WR' completes the circuit through the motor 38 in the following manner. Current flows from positive battery 225, conductor 261, through contact 214c of the circuit controller 214, conductor 279, contact B'', conductor 263, terminal 264, conductor 265, contact 106b of the circuit controller 46, conductor 266, conductor 231, terminal 232, field winding F of the motor 38, terminal 233, conductor 234, contact 188b dropped, conductor 235, terminal 236, conductor 237, conductor 238, contact 208 of the relay WR', conductor 239, terminal 240, the armature of the motor 38, terminal 241, conductor 242, contact 209 dropped, of the relay WR', conductor 243, conductor 244, terminal 245, conductor 246, contact 188c dropped, conductor 247, terminal 248 to negative battery 158. Reversal of the motor 38 restores the motion plate 30b to its original position, locking the switch mechanism and returning all parts thereof to the position normally occupied. As the motion plate 30b reaches its normal position, the contact 106b of the circuit controller 46 opens, and the circuit to the motor is broken, stopping the motor.

The stick relay SN is useful when the small lever 22 is moved from the position R', to the position C', and then back to the position R' again. The stick relay SN is energized when the small lever 22 is at the position C' and the large lever 12b is in the reverse position, current flowing from positive battery 135, through conductor 220, contact CB, contact member 214b dropped, conductor 280, through the relay SN to negative battery 281. When the relay SN is energized, its contacts 210, 211 are raised, completing a circuit to the relay WR', through the conductor 282. When the relay SN is energized, and the switch throwing lever 12b is moved from reverse to normal position, the relay is maintained by a circuit from positive battery 135 through conductor 220, contact CB, contact member 214b lifted, conductor 283, contact 210 of the relay SN, through the relay SN to negative battery 281.

It will thus be apparent that the provision of the stick relays SN, SR makes possible a restoration of the switch mechanism to the desired con-

dition whenever the operator has made a false movement of the small lever 22 and desires to correct that movement without throwing the switch.

It will also be observed that when the switch is trialed through, or the switch points are distorted by dragging equipment, through the action of the point detector rod 7 and the electrical contacts 67a, 67b, the circuit to the relay SS is broken, making it impossible for the operator to control the switch from the remote station, and giving the operator an indication of the defective condition.

Both forms of apparatus herein described are characterized by safety and positiveness of operation under conditions of normal and abnormal service, and capacity for adjustment to conform to switch point openings of various sizes. Both forms of apparatus utilize the full throw of the switch throwing lever for moving the point rails of the switch, reducing the power required for movement of the switch, and adding to the convenience of the operator.

While I have described my invention with reference to two examples of the practice thereof, and with reference to a manually operated switch, describing with particularity specific apparatus which may be employed, it will be readily apparent that many changes may be made in the form of the apparatus herein described, both with respect to the devices employed at the switch and those employed at the control station, and that certain features of the invention may be used to advantage without a corresponding use of other features, all without departing from the spirit of the invention as defined in the annexed claims.

Having thus described my invention, I claim:

1. In a switch mechanism of the class described, switch operating and switch locking rods directly connected to the switch points, means at the switch with its movement controlled electrically from a remote station for performing all the operations required for locking and unlocking the locking rod, and means controlled mechanically from said remote station for actuating said switch operating rod, said electrically controlled means operating as an antecedent condition to the operation of said mechanically controlled means.

2. In a switch mechanism of the class described, switch operating and switch locking rods directly connected to the switch points, means at the switch with its movement controlled electrically from a remote station for locking and unlocking said locking rod, and a switch throwing device at said remote station for actuating said switch operating rod, the full movement of said switch throwing device being employed to throw the switch.

3. In a switch mechanism of the class described, switch operating and switch locking means directly connected to the switch points, an electric motor at the switch for performing all of the operations required for locking and unlocking the switch locking means, a switch throwing device for actuating said switch operating means, and electric means associated with said switch throwing device and motor whereby the switch is automatically unlocked before the initial movement of the switch throwing device and automatically locked after the final movement of the switch throwing device.

4. In a switch mechanism of the class described, a switch operating rod and a lock rod

connected to the switch points, means controlled electrically from a remote station for locking and unlocking said lock rod, and mechanical means including a switch throwing lever at said remote station for moving said operating rod, the full movement of said lever being employed to throw the switch.

5. In a switch mechanism of the class described, a switch operating rod and a lock rod directly connected to the switch points, means for locking and unlocking said lock rod, a remote controlled reversible motor disposed adjacent to the switch for operating said means, and a remote switch throwing device for moving said operating rod, the full stroke of said switch throwing device being employed to throw the switch.

6. In a switch mechanism of the class described, a switch operating rod and a lock rod directly connected to the switch points, means at the switch normally blocking the movement of both said rods, a remote controlled motor, and mechanism actuated by said motor for performing all of the operations required for locking and unlocking the lock rod and effecting the removal of said blocking means thereby to permit free movement of said switch operating rod and said lock rod.

7. In a switch mechanism of the class described, a switch operating rod and a lock rod connected to the switch points, means normally blocking the movement of said operating rod, additional means normally blocking said lock rod, a slide bar connected to both said blocking means, and a remote controlled motor for operating said slide bar.

8. In a switch mechanism of the class described, a lock rod connected to the switch points, a slide bar for locking and releasing said lock rod, a remote controlled reversible motor for moving said slide bar, a circuit controller having contacts for opening and closing the circuit to said motor, and means mechanically connecting said circuit controller and slide bar whereby upon the unlocking of the slide bar the circuit controller is moved to a position causing the motor to stop.

9. In a switch mechanism of the class described, a lock rod connected to the switch points, a slide bar adapted to engage and release said lock rod to lock and unlock the same respectively, a remote controlled reversible motor for moving said slide bar, a circuit controller having contacts for opening and closing the circuit to said motor, and a mechanical connection between said circuit controller and slide bar whereby the movement of said slide bar from engaged to released position with respect to the lock rod imparts a movement to said circuit controller causing the motor to stop.

10. In a switch mechanism of the class described, a switch operating rod and a point detector rod connected to the switch points, a switch throwing device connected to said switch operating rod, means controlled electrically and adapted to obstruct the regular operation of said switch throwing device and thus to indicate to the operator abnormal movements of the switch, a circuit controller operated by the movement of the point detector rod and in circuit with the indicating means aforesaid, and mechanism including a crank arm with cam surfaces engaged by said point detector rod connecting said point detector rod and circuit controller, said cam surfaces being adjustable to conform with switch point openings of varying size.

11. In a switch mechanism of the class described, a switch operating rod, a lock rod, and a point detector rod connected to the switch points, a slide bar for locking and releasing said lock rod, a circuit controller responsive to the movement of said slide bar, a switch throwing device connected to said switch operating rod, means controlled electrically and adapted to obstruct the regular operation of said switch throwing device and thus to indicate to the operator abnormal movements of the switch, and an additional circuit controller operated by the movement of the point detector rod, both said circuit controllers being in circuit with the indicating means aforesaid.

12. In a switch mechanism of the class described, a switch operating rod, a lock rod, and a point detector rod connected to the switch points, mechanism for locking and releasing said lock rod, an electric motor for operating said mechanism, a circuit controller responsive to the movement of said mechanism, a switch throwing device connected to said switch operating rod, means controlled electrically and adapted to obstruct the regular operation of said switch throwing device and thus to indicate to the operator abnormal movements of the switch, and an additional circuit controller operated by the movement of the point detector rod, said circuit controllers controlling the operation of the motor and of the indicating means aforesaid.

13. In a switch mechanism of the class described, a switch operating rod, a lock rod and a point detector rod connected to the switch points, means for locking and releasing the lock rod, an electric contact device forming part of a switch position indicating circuit, mechanism responsive to the movement of said locking and releasing means and rendering said contact device inoperative while said lock rod is released, and mechanism responsive to the movement of the point detector rod rendering said contact device inoperative only while the switch points are at either limit of their travel.

14. In a switch mechanism of the class described, a switch operating rod, a lock rod and a point detector rod connected to the switch points, a slide bar for locking and releasing the lock rod, an electric contact device forming part of a switch position indicating circuit, means tending to operate said contact device, mechanism responsive to the movement of the slide bar and obstructing operation of said contact device only while the lock rod is released, and mechanism responsive to the movement of the point detector rod obstructing operation of said contact device while the switch points are at either limit of their travel and otherwise not obstructing such operation, whereby said contact device is permitted to operate only when the switch points are moved while the lock rod is engaged by the slide bar.

15. In a switch mechanism of the class described, a switch operating rod and a lock rod connected to the switch points, means for locking and unlocking said lock rod including a movable member and a deformable arm attached to said member in fixed relation thereto, and a remote controlled pipe line for moving said operating rod, said deformable arm normally blocking movement of the switch operating rod by means of said pipe line and offering such resistance to deformation that it will give way before parting of the switch operating rod but not before parting of the pipe line.

16. In a switch mechanism of the class described, a switch operating rod and a lock rod connected to the switch points, means for locking and unlocking said lock rod including a movable member having a pair of torsionally deformable arms attached to said member in fixed relation thereto, and a remote controlled pipe line for moving said operating rod, said deformable arms serving to prevent movement of the switch operating rod by means of said pipe line and offering such resistance to deformation that they will give way before parting of the switch operating rod but not before parting of the pipe line.
17. In a switch mechanism of the class described, a switch operating rod and a lock rod connected to the switch points, means for locking and unlocking said lock rod including a movable member having a socket therein, a remote controlled pipe line for moving said operating rod, and blocking means normally obstructing movement of the operating rod, said means comprising a shank fitting in the socket of said movable member, and an arm projecting radially from the axis of said shank, said arm offering such resistance to torsional stress that it will give way before parting of the operating rod, but not before parting of the pipe line, under external forces applied at the switch and pipe line respectively.
18. In a switch mechanism of the class described, a switch operating rod and a lock rod connected to the switch points, means for locking and unlocking said lock rod including a movable member having a socket therein, a stationary projection disposed adjacent to said socket, and blocking means normally obstructing movement of the operating rod, said blocking means comprising a shank fitting in the socket of said movable member, an arm projecting radially from the axis of said shank in the path of the operating rod, and an additional arm disposed at an angle to the first mentioned arm and normally clear of the stationary projection aforesaid but adapted to engage said projection when said first arm is stressed torsionally beyond its elastic limit.
19. In a switch mechanism of the class described, a switch operating rod and a lock rod connected to the switch points, a slide bar adapted to engage and release said lock rod, a remote controlled motor for moving said slide bar, a circuit controller in circuit with said motor and operated by said slide bar, a remote switch throwing device for moving said operating rod, and means associated with the switch throwing device for closing the circuit to said motor to start the same and thereby release the lock rod preparatory to movement of the operating rod, said circuit controller having contacts for opening the circuit to said motor to stop the same after the slide bar has moved to a position releasing the lock rod.
20. In a switch mechanism of the class described, a switch operating rod and a lock rod connected to the switch points, a slide bar adapted to engage and release said lock rod, a remote controlled reversible motor for moving said slide bar, a circuit controller in circuit with said motor and operated by said slide bar, a remote switch throwing device for moving said operating rod, means associated with the switch throwing device for closing the circuit to said motor to start the same and thereby release the lock rod preparatory to movement of the operating rod, said circuit controller having contacts for opening the circuit to said motor to stop the same after the slide bar has moved to a position releasing the lock rod, and means for changing the polarity of said motor to reverse the direction of the same.
21. In a switch mechanism of the class described, a switch operating rod and a lock rod connected to the switch points, a pair of slide bars adapted to engage and release said lock rod whereby said lock rod may be locked in either of two extreme positions, a remote controlled reversible motor for moving said slide bars, a remote switch throwing device for moving said operating rod, means associated with the switch throwing device for closing the circuit to the motor to start the same preparatory to movement of the operating rod, and means for changing the polarity of said motor after the switch has been thrown and locked.
22. In a switch mechanism of the class described, switch operating and switch locking means connected to the switch points, a motor at the switch for actuating said locking means, a remote switch throwing device for actuating said switch operating means, and a control lever mechanically connected to the switch throwing device by cross locking mechanism, the movements of said control lever governing the starting and stopping of said motor, the full movement of said switch throwing device being employed to throw the switch.
23. In a switch mechanism of the class described, switch operating and switch locking means connected to the switch points, a motor at the switch for actuating said locking means, a remote switch throwing device for actuating said switch operating means, a control lever mechanically connected to the switch throwing device by cross locking mechanism, the movements of said control lever governing the starting and stopping of said motor, and means whereby, when the control lever is moved from its normal position with resulting movement of said motor and locking means, the locking means may be restored to normal condition without operation of said switch throwing device.

CHARLES C. THORN.
